CLAIM

(57) The ornamental design for a mounted air purifier, as shown and described.

DESCRIPTION

FIG. 1 is a first perspective view from the bottom up of a mounted air purifier showing our new design;

FIG. 2 is side plan view thereof;

FIG. 3 is a top-down plan view thereof;

FIG. 4 is a second perspective view thereof from the bottom up at an increased angle as compared to FIG. 1; and,

FIG. 5 is a bottom-up plan view thereof.

The broken lines show portions of the mounted air purifier that form no part of the claimed design.

1 Claim, 5 Drawing Sheets
